(57) **CLAIM**

The ornamental design for an electronic device holder, as shown and described.

DESCRIPTION

FIG. 1 is a perspective view of an electronic device holder, showing my new design in a first configuration of use; FIG. 2 is a perspective view of the electronic device holder of FIG. 1, shown in a second configuration of use; FIG. 3 is a left side elevational view of the electronic device holder of FIG. 1, shown in a first configuration of use; FIG. 4 is a right side elevational view thereof; FIG. 5 is a top plan view thereof; FIG. 6 is a bottom plan view thereof; FIG. 7 is a rear elevational view thereof; FIG. 8 is a front elevational view thereof; FIG. 9 is a front elevational view of the electronic device holder of FIG. 1, shown in a third configuration of use; FIG. 10 is a rear elevational view of the electronic device holder of FIG. 1, shown in a fourth configuration of use; and, FIG. 11 is a rear elevational view thereof, shown in an environment of use.

Broken lines illustrate portions of the electronic device holder that form no part of the claimed design. Additional broken lines in FIG. 11 showing an electronic device, illustrate environmental subject matter and form no part of the claimed design.

1 Claim, 6 Drawing Sheets
